UNITED STATES PATENT OFFICE.

JAMES F. CARBERRY, OF WORCESTER, MASSACHUSETTS.

LOOM-TEMPLE.

SPECIFICATION forming part of Letters Patent No. 763,462, dated June 28, 1904.

Application filed January 13, 1904. Serial No. 188,880. (No model.)

To all whom it may concern:

Be it known that I, JAMES F. CARBERRY, a citizen of the United States, residing at Worcester, in the county of Worcester and State of Massachusetts, have invented certain new and useful Improvements in Loom-Temples, of which the following is a specification.

In loom-temple construction and in their application to the breast-beam of the loom it has heretofore been proposed to mount the temple-head upon a bar substantially parallel to the breast-beam, such bar being pivoted at one end and having a detachable connection with a bracket at its opposite end. It has likewise been proposed to provide means whereby the temple-head could be adjusted on the bar to place the axis of rotation of the temple-roll at the desired inclination to the warp of the cloth being woven or parallel to the line of the reed, as in United States Patent No. 237,169. One form of such means comprised a transverse opening in the temple-head having one side wall of said opening concave to receive a rocking shoe, and passing through the opposite wall of the opening were two adjusting or clamping screws.

The present invention has for its object to simplify the constructions referred to and by dispensing with the rocking shoe and detachable connection for one end of the temple-bar provide a simple and efficient device of few parts, which will readily yield under the action of the lay and wherein the temple-head may be adjusted to any desired angle upon the temple-bar without the aid of a separate rocking shoe.

With these general objects in view the invention consists of the parts and combinations hereinafter more fully described, and definitely pointed out in the claims.

The figure of the drawing shows in general under plan view a device embodying the present invention, some of the parts being broken away to show the details beyond.

In the drawing, A represents a portion of a breast-beam, to which are adjustably secured the brackets A' B, as by bolts and nuts, as usual. The bracket A' has its end split and offset, as shown, and to one of the split ends

a', said temple-bar being held in engagement with its pivot a' by means of the other offset a'' of bracket A', which engages the opposite side of the temple-bar. The bracket A'' is arranged some distance from the bracket A', and the end b thereof is carried downward and backward, terminating at b', to provide a rest for the free end of the temple-bar, which being engaged between the offset portions b b' of the bracket is free to move back and forth as the temple-bar swings upon its pivot. A spring D, connected to bracket A', bears at its end d upon the temple-bar C to normally force the free end of the temple-bar toward the lay or away from the breast-beam A, an adjusting device d' serving to regulate the force of the spring.

Mounted upon the temple-bar C, so as to be adjusted longitudinally thereon, is the temple-head E, carrying any usual or desired form of temple-roll E'. The arm E'' of the temple-head is provided with an opening E''' therethrough, said opening being larger at one end, e, than at the other, e', and threaded through the opposite walls near the larger part of the opening E''' are the adjusting-screws f f', which at their respective ends bear upon opposite sides of the temple-bar C. It will be noted that the opening E''' at the smaller end e' is just large enough to embrace and bear upon the opposite sides of the temple-bar with a working fit to hold the temple-head in position, while the larger end of the opening E''' is such that considerable play is afforded. From this construction it will be seen that the edges f' f' of the temple-head opening E''' act as bearing-points about which the temple-head may be adjusted by means of the adjusting-screws f f' and that when the adjusting-screws f f' are screwed up tight against opposite sides of the temple-bar the temple-head will be firmly held by the points f' f' and the ends of the screws f f'. Obviously to adjust the angular relation of the temple-head and temple-bar, and thereby change the inclination of the temple-head and roll with respect to the warp-threads or reed, it is simply necessary to loosen one screw and tighten up on the opposite screw, whereupon the temple-head will turn substantially about the bearings f' f'.

If desired, in addition to the adjusting-screws *f* the temple-head may be further secured in position by means of set-screws, as *g g*, shown in dotted lines as passing through 5 the temple-head and bearing upon the flat surface of the temple-bar.

By means herein described for adjusting the angular position of the temple-head or temple upon the temple-bar no loose parts are employed, which are liable to become lost, and 10 simplicity of action is afforded.

Having thus described my invention, what I claim, and desire to secure by Letters Patent, 15 is—

15 1. In a device of the character described, the combination of a temple-bar, a temple-head having an opening therethrough larger at one end than at the other, and means adjacent the larger end of the opening for adjusting 20 the angular position of the head on said bar.

2. In a device of the character described, the combination of a temple-bar, a temple-head having an opening therethrough larger 25 at one end than at the other and mounted upon

said bar, an adjusting-screw passing through the opposite walls of the opening near the larger end for adjusting the angular position of the temple-head on the temple-bar.

3. In a device of the character described, 30 the combination of a temple-bar, a bracket to which one end of said bar is pivotally connected, a second bracket having offset portions between which the free end of the temple-bar is loosely supported, a spring for normally 35 forcing the free end of the temple-bar toward the lay, and a temple-head adjustably secured upon said temple-bar.

4. In a device of the character described, the combination of a temple-bar, a temple- 40 head longitudinally movable on said bar and having an opening therethrough enlarged at one end, and means for adjusting the angular position of the head on said bar.

In testimony whereof I affix my signature in 45 presence of two witnesses.

JAMES F. CARBERRY.
